UNITED STATES PATENT OFFICE.

NEWTON L. WARREN, OF MACON, GEORGIA.

UPRIGHT BOILER.

SPECIFICATION forming part of Letters Patent No. 762,106, dated June 7, 1904.

Application filed November 19, 1903. Serial No. 181,794. (No model.)

To all whom it may concern:

Be it known that I, NEWTON L. WARREN, a citizen of the United States, and a resident of Macon, in the county of Bibb and State of Georgia, have invented a new and Improved 5 Upright Boiler, of which the following is a full, clear, and exact description.

The object of the invention is to provide a new and improved upright boiler arranged to 10 permit convenient entrance of the operator for cleaning the interior of the boiler and to give ready access to the smoke-tubes to clean the same.

The invention consists of novel features and 15 parts and combinations of the same, as will be more fully described hereinafter and then pointed out in the claims.

A practical embodiment of the invention is represented in the accompanying drawings, 20 forming a part of this specification, in which similar characters of reference indicate corresponding parts in all the views.

Figure 1 is a sectional side elevation of the improvement. Fig. 2 is a front view of the 25 same, parts being in section; and Fig. 3 is an inverted sectional plan view of the same on the line 3-3 of Fig. 1.

In the brickwork A of the boiler-furnace is arranged a fire-box B, provided with a grate 30 C, below which is arranged an ash-pit D, and the said fire-box and ash-pit are provided with the usual doors E and E'.

The fire-box B is connected by a bridge-wall F with a combustion-chamber G, over 35 which is set a boiler-shell H, disposed vertically and supported by suitable brackets I on the brickwork A, as plainly indicated in the drawings. The boiler-shell H is closed at top and bottom by heads J and J', connected with

40 each other by smoke flues or tubes K, of which the innermost rows K' are in the form of stay-tubes, as plainly indicated in Figs. 1 and 2. The middle portions J² and J³ of the heads J and J' are arched and extend diametrically 45 adjacent to the innermost rows K' of the tubes K, so as to leave considerable space in the middle portion of the boiler for the entrance of the operator to clean the boiler interiorly whenever it is deemed necessary to

do so. Access to the space in the middle portion of the boiler is had through a suitable manhole H', leading to the space near the lower end of the shell, it being, however, expressly understood that the said space extends from the arched middle portion J³ of the bottom head J' to the corresponding arched middle portion J² of the top head J and through the entire diameter of the boiler, as plainly indicated in Fig. 3.

It is further understood that by arching 60 the middle portions J² and J³ of the boiler-heads and making the adjacent rows K' of the boiler-tubes K in the form of stay-tubes the desired and necessary strength is given to the boiler-heads at these points. 65

From the middle portion J² of the top boiler-head J leads a steam-pipe L for carrying off the steam, and the said middle portion J² is also provided with pipes N for carrying safety-valves. From the middle portion J³ of the lower boiler-head J' leads a blow-off pipe O, as indicated in Fig. 1.

It is understood that the lower ends of the boiler-tubes K open directly into the combustion-chamber G, and the upper ends of the 75 said tubes open into a smoke-box P, provided on top with hinged doors P', which when open give convenient access to the upper ends of the tubes K to allow of conveniently cleaning the same. The smoke-box P has a side outlet 80 P² for connection with the chimney, and the smoke-box is surrounded by a suitable platform Q for the operator to stand on when cleaning the tubes K, as above mentioned.

A feed-pipe R for supplying the boiler with 85 water is illustrated in Figs. 1 and 2, and the boiler is provided with the usual water-gage S and the steam-gage T.

Having thus described my invention, I claim as new and desire to secure by Letters Patent— 90

1. A boiler provided with a shell, boiler-heads for the same, provided with arched portions extending diametrically, and boiler-tubes connecting the heads with each other at the non-arched portions, to leave a clear space 95 in the middle of the boiler, as set forth.

2. A boiler provided with a shell, boiler-heads for the same, provided with arched por-

tions extending diametrically, boiler-tubes connecting the heads with each other at the non-arched portions, to leave a clear space in the middle of the boiler, and a manhole in the said shell, opening into the said clear space, as set forth.

3. A boiler provided with a shell, boiler-heads for the same, provided with arched portions extending diametrically, boiler-tubes connecting the heads with each other at the non-arched portions, to leave a clear space in the middle of the boiler, and a steam-outlet at the arched portion of the upper head, as set forth.

15 4. A boiler provided with a shell, boiler-heads for the same, provided with arched portions extending diametrically, boiler-tubes connecting the heads with each other at the non-arched portions, to leave a clear space in the middle of the boiler, and a blow-off pipe 20 leading from the arched portion of the lower head, as set forth.

5. A boiler provided with a shell, boiler-heads for the same, provided with arched portions extending diametrically, boiler-tubes connecting the heads with each other at the non-arched portions, to leave a clear space in the middle of the boiler, a steam-outlet and safety-valves on the arched portion of the upper head, and a blow-off pipe leading from the arched portion of the lower head, as set forth.

25 6. A boiler provided with a shell, boiler-heads for the same, provided with arched portions extending diametrically, and boiler-tubes connecting the heads with each other at the non-arched portions, to leave a clear space in the middle of the boiler, the innermost 30 rows of tubes, adjacent to the arched portions

of the boiler-heads, being stay-tubes, as set forth.

7. A boiler comprising a fire-box, a combustion-chamber, a bridge-wall between the fire-box and the combustion-chamber, an upright boiler-shell set over the combustion-chamber, boiler-heads in the said shell, having arched middle portions, boiler-tubes connecting the said heads with each other at the non-arched portions, and a smoke-box on the upper boiler-head, having hinged doors for giving access to the upper ends of the said boiler-tubes, as set forth.

8. A boiler comprising a shell, boiler-heads for the same provided with parallel arched portions extending diametrically across the boiler from side to side thereof, boiler-tubes connecting the heads with each other at the non-arched portions to leave a clear space in the middle of the boiler, the innermost rows of tubes adjacent the arched portions of the boiler-heads being stay-tubes, a steam-outlet and safety-valves on the arched portion of the upper head, a blow-off pipe leading from the arched portion of the lower head, a manhole in the side of the shell near the lower end thereof opening into the space between the parallel arched portions of the boiler-heads, and feed-pipes in said space at the side of the boiler diametrically opposite the manhole.

In testimony whereof I have signed my name to this specification in the presence of two sub-
scribing witnesses.

NEWTON L. WARREN.
